CLAIM

The ornamental design for the lid for beverage container, as shown and described.

DESCRIPTION

FIG. 1 is a front perspective view of the lid for beverage container with the cap in the closed position and the handle in first position;

FIG. 2 is a front view thereof;

FIG. 3 is a rear view thereof;

FIG. 4 is left side view thereof;

FIG. 5 is a right side view thereof;

FIG. 6 is a top view thereof;

FIG. 7 is a bottom view thereof;

FIG. 8 is a front perspective view of the lid for beverage container with the cap in the open position and the handle in first position;

FIG. 9 is a front view thereof;

FIG. 10 is a rear view thereof;

FIG. 11 is left side view thereof;

FIG. 12 is a right side view thereof;

FIG. 13 is a top view thereof;

FIG. 14 is a bottom view thereof; and,

FIG. 15 is a left side view of the lid for beverage container with the cap in the closed position and the handle in the second position.

The broken lines depict portions of the lid for beverage container that form no part of the claimed design.
